Assistant Examiner — Jessica M Gebhart

(57) CLAIM

The ornamental design for a wallet as shown and described.

DESCRIPTION

The patent or application file contains at least one drawing executed in color. Copies of this patent or patent application publication with color drawing(s) will be provided by the Office upon request and payment of the necessary fee.

1. Wallet

1.1 : Perspective

1.2 : Front

1.3 : Back

1.4 : Right

1.5 : Left

1.6 : Top

1.7 : Bottom

1.8 : Perspective

1.9 : Detail view

The characteristic features of the design lie in the combination of the shape and decorative rings of three different colors on the front side of the wallet; protection for color is claimed.
